HENRICUS GOOSKENS AND PIETER LEYDENS, OF EINDHOVEN, NETHERLANDS, AS
SIGNORS TO GENERAL ELECTRIC COMPANY, OF SCHENECTADY, NEW YORK

MANUFACTURE OF ELECTRIC INCANDESCENT LAMPS OR SIMILAR DEVICES

Application filed March 25, 1930, Serial No. 438,630, and in the Netherlands March 23, 1929.

Our invention relates to electric lamps and similar devices such as vacuum tubes, and more particularly to such devices comprising inner and outer bulbs which are either evacuated or gas filled. The object of our invention is to provide a construction which will be more devoid of strains and therefore more rugged. According to our invention we provide a mount which is axially disposed and comprises the well-known flared stem tube. This mount comprises one or more light sources, for example, two filaments, one of which is disposed within the inner bulb, as hereinafter explained, and the other is disposed within the outer bulb but outside of the inner bulb. The mount carries the necessary leading-in wires for these filaments. However, our invention is also applicable to electric lamps comprising other forms of light sources, such as the tungsten arc, etc. The neck of the inner bulb is formed with a flange. During the sealing-in operation, the mount and inner bulb are so supported that the flange of the latter is just above and slightly removed from that of the mount stem tube. The result is that when the outer bulb is placed over this assembly, the neck thereof may be simultaneously sealed to both flanges, thus producing an integral structure. In the drawing, Fig. 1 is a vertical section of an incandescent lamp consisting of an embodiment of our invention.

In the drawing is shown a completed lamp comprising our invention and consisting of the outer bulb 10, the inner bulb 11, and an axially disposed mount comprising the flared stem tube 12 which is made according to the process disclosed in Mitchell and White Patent 1,423,956 and carries the exhaust tube 13 communicating with the aperture 14. There are two pairs of leads 14' and 15 respectively. These are sealed in the stem press 16, the former being connected to the filament 17, and the latter to the filament 18, which are both supported in the usual manner by metal hooks carried by the central glass arbor 19. Suitable insulating sleeves 20 of refractory material, such as high-melting point glass, are provided for the portions of the leads 15 which are disposed in the region of the fila-

ment 17. The leads 15 also pass through a clamped sealed glass portion 21 which is formed from a portion of the inner bulb 11 which surrounds the mount. The said inner bulb extends parallel with the mount and the neck thereof has a flange 23 similar to the flange 24 of the stem tube. The neck also has an aperture 25 so that the outer bulb and inner bulb may be exhausted at the same time, through the exhaust tube 13 which is then sealed up. During the sealing-in operation the outer bulb 10 is placed over the vertically supported assembly of inner bulb and mount, and the neck 26 thereof is fused to the flanges 23 and 24 simultaneously. 65

What we claim is:

1. An electric lamp or similar device comprising inner and outer bulbs and an axially disposed filament mount comprising a flared stem tube, the former extending through said inner bulb, the neck of said inner bulb being also flared and both of said flares being parallel and integrally united to be neck of said outer bulb. 70

2. An electric lamp or similar device comprising inner and outer bulbs, said outer bulb having a neck, an axially disposed filament mount passing through said inner bulb into the outer bulb, a flared stem tube, the neck of said inner bulb being also flared parallel with the flare of the stem, said flares being integrally united to the neck of the outer bulb, and a filament carried by the mount and located between the inner and outer bulbs. 75

3. An electric lamp or similar device comprising inner and outer bulbs, said outer bulb having a neck, an axially disposed filament mount passing through said inner bulb into the outer bulb, a flared stem tube, the neck of said inner bulb being also flared parallel with the flare of the stem, said flares being integrally united to the neck of the outer bulb, and a pair of filaments carried on the mount one within the inner bulb and the other in the outer bulb. 85

In testimony whereof we have signed our names to this specification.

HENRICUS GOOSKENS.
PIETER LEYDENS.
